J. W. PARKS,

OIL CUP.

APPLICATION FILED MAY 17, 1917.

1,277,636.

Patented Sept. 3, 1918.

UNITED STATES PATENT OFFICE.

JAMES W. PARKS, OF AUSTIN, TEXAS.

OIL-CUP.

1,277,636.

Specification of Letters Patent. Patented Sept. 3, 1918.

Application filed May 17, 1917. Serial No. 169,277.

To all whom it may concern:

Be it known that I, JAMES W. PARKS, a citizen of the United States, and a resident of Austin, in the county of Travis and 5 State of Texas, have invented an Improvement in Oil-Cups, of which the following is a specification.

My invention is an improvement in oil cups, and has for its object to provide a 10 device of the character specified, especially adapted for jewelers' use, wherein the receptacle for the oil is supported in a suitable casing having a cover for the receptacle hinged to the casing, and carrying a 15 holder for the oiler, the cover being normally spring-pressed into open position, and being connected to mechanism controlled by the insertion of the oiler in the holder for closing the cover and holding said cover 20 closed.

In the drawings:

Figure 1 is a perspective view of the improved oiler in open position.

Fig. 2 is a vertical section with the oiler 25 open.

Fig. 3 is a view similar to Fig. 2 with the oiler closed.

Fig. 4 is a perspective view of the moving parts of the oiler removed.

30 In the present embodiment of the invention a suitable base 1 is provided of wood or like material, having in its lower end a conical or tapering recess 2, and in its upper end a cylindrical recess 3. The recess 3 is covered by a disk or plate 4, having a central opening, in which is arranged an oil cup 5, 35 in the form of a disk of suitable material, as, for instance, glass, having at its center a depression 6 for receiving the oil.

40 The plate or disk 4 has an angular bar 7 connected therewith, the said bar consisting of a vertical portion extending downwardly into the recess, and a horizontal portion extending toward the center of the recess, and this horizontal portion is connected by a yoke-shaped member consisting of a body 8 and arms 9 with the opposite sides of the under face of the disk at points 90° removed from the connection of the bar 7.

45 These arms 9 at their junction with the disk 4 extend forwardly, as indicated at 10, and then downwardly alongside each other, as indicated at 12, and an elbow lever is pivoted between the depending portions 12 at the junction of the arms 13 and 14 of the 55 elbow lever. The arm 13 extends rearwardly

through a slot 15 in the vertical portion of the angle bar 7, and the said arm of the lever is provided at the end remote from the pivotal connection with an upstanding 60 vertically slotted portion 16. The arm 14 is forked, and a wheel 17 is journaled between the arms of the fork.

A concavo-convex lid or cover 18 is pivoted to the disk 4, as indicated at 19, and this lid has a rearwardly extending lug 20, which is connected by a link 21 with the slot of the portion 16 of the elbow lever. This link passes downwardly through an opening in the disk 4, and the peripheral surface of the 70 wheel 17 extends through a vertical slot 22 in a cylindrical holder 23 which is mounted at the front of the base 1, in a vertical opening 24 in the base. The upper end of this holder is funnel-shaped, as indicated at 25, 75 and the said holder is adapted to receive the oiler indicated at 26. This oiler has a tapering portion 27 intermediate its ends, at such a point in the length of the oiler, that when the oiler is inserted in the holder, with the ferrule 28 thereof in engagement with the tapering top of the holder the tapering portion 27 of the oiler will engage the wheel 17, and will swing the elbow lever 13-14 in a direction to move the rear end of the arm 85 13 upwardly. A coil spring 29 is connected with the arm 13, the said spring acting normally to force the rear end of the arm 13 of the lever downwardly. One portion of this spring is held between a plate 29^a and 90 the oil cup 5, and the other portion engages the arm of the lever.

In operation, when the parts are in the position of Fig. 3, the tapering portion 27 of the oiler will engage the wheel 17, swinging the elbow lever 13-14 in a direction to move the rear end of the arm 13 of the lever upwardly to close the cover 18. When the oiler is withdrawn, the spring 29 immediately throws the rear end of the arm 13 of the lever downwardly, thus opening the cover. Thus the operator, with one hand, may remove the oiler and open the receptacle at the same time. The body 8 of the yoke-shaped member 8-9, and the horizontal portion of the angle bar 7 where they overlap have a threaded opening 30, which is adapted to receive a screw 31, which is passed upwardly through the conical weight 32 arranged in the recess 2, and connects 100 the weight, the disk 4, and the base 1 together. This weight holds the parts suffi- 105 110

ciently steady to permit the oiler to be worked with a single hand, without danger of overturning the same.

It will be noticed from an inspection of 5 Figs. 2 and 3 that the holder 6 for the oil has its peripheral surface or edge beveled in two directions. One of these bevels is engaged with the opening in the plate 4 and the engagement limits upward movement of 10 the holder. The plate 29^a has its ends notched, to receive the arms 9 of the yoke-shaped member, and since these arms incline inwardly toward their lower ends, the plate is held from downward movement, 15 thus supporting the oil holder.

I claim:

1. A device of the character specified, comprising a base having a recess in its upper end, a disk covering said recess and carrying an oil receptacle, and having a depending holder for an oiler at one side, and a cover hinged to the other side to close over the receptacle, a spring normally pressing the cover open, and means connected to the 25 cover and extending into the holder and

controlled by the insertion of the oiler in the holder for closing the cover, said base having an axial opening, a screw passing through the opening, the disk having a nut connected therewith for engagement by the 30 screw to hold the disk in place.

2. A device of the character specified, comprising a base having a recess in its upper end, a disk covering said recess and carrying an oil receptacle, and having a depending holder for an oiler at one side, and a cover hinged to the other side to close over the receptacle, a spring normally pressing the cover open, means connected to the cover and extending into the holder and controlled by the insertion of the oiler in the holder for closing the cover, said base having a recess in its lower end, a weight in the lower recess, and a detachable connection between the weight and the disk. 35 40
